UNITED STATES PATENT OFFICE.

BENJAMIN LIPPER, OF PHILADELPHIA, PENNSYLVANIA, ASSIGNOR TO
AUGUSTUS A. LAZARUS, ISAAC A. SCHWARZ, AND BENJAMIN LIPPER,
OF SAME PLACE.

DESIGN FOR DRESS-TRIMMING.

SPECIFICATION forming part of Design No. 21,263, dated December 22, 1891.

Application filed November 30, 1891. Serial No. 413,595. Term of patent 3½ years.

To all whom it may concern:

Be it known that I, BENJAMIN LIPPER, a citizen of the United States, and a resident of Philadelphia, Pennsylvania, have invented a
5 Design for Dress-Trimming, of which the following is a specification.

My design is fully shown in the accompanying drawing, which represents a face view of a short piece of the trimming.

- 10 The essential features of novelty in the design are the band or tape *a*, the narrow-edge bands *b*, and the cord which passes through said edge bands and lies on the face of the band or tape *a*, said cord forming inwardly-
15 projecting loops *d*, first at one edge and then at the opposite edge of said band or tape, these loops being connected by reversely-in-

clined crossing-cords *f*. The trimming shown in the drawing also has an edging or border composed of looped cords *g*, passing through 20 the bands *b*; but the character of the edging or border is immaterial, this being a minor feature of the design.

I claim—

The design for a dress-trimming, substantially as described, and as shown in the accompanying drawing.

In testimony whereof I have signed my name to this specification in the presence of two subscribing witnesses.

BENJAMIN LIPPER.

Witnesses:

EUGENE ELTERICH,
HARRY SMITH.
